Notice of Allowance Dated Dec. 12, 2011, for U.S. Appl. No. 29/404,901.

Primary Examiner — Paula Greene

(74) Attorney, Agent, or Firm — Alston & Bird LLP

(57) **CLAIM**

The ornamental design for a stackable container, as shown and described.

DESCRIPTION

FIG. 1 is a perspective view of a stackable container showing our new design;

FIG. 2 is an elevation front view of the stackable container shown in FIG. 1;

FIG. 3 is an elevation side view of the stackable container shown in FIG. 1, the opposite side view being a mirror image thereof;

FIG. 4 is an elevation rear view of the stackable container shown in FIG. 1;

FIG. 5 is a plan top view of the stackable container shown in FIG. 1; and,

FIG. 6 is a bottom plan view of a stackable container of FIG. 1.

The broken lines shown in the drawing disclosure are for illustrative purposes only and form no part of the claimed design.

1 Claim, 6 Drawing Sheets
